No. 894,632.

PATENTED JULY 28, 1908.

C. H. HALL & J. ELDRIDGE.
GOLD SEPARATOR AND AMALGAMATOR.

APPLICATION FILED FEB. 11, 1907.

UNITED STATES PATENT OFFICE.

CHARLES H. HALL AND JOHN ELDRIDGE, OF ASTORIA, OREGON.

GOLD SEPARATOR AND AMALGAMATOR.

No. 894,632.

Specification of Letters Patent.

Patented July 28, 1908.

Application filed February 11, 1907. Serial No. 356,743.

To all whom it may concern:

Be it known that we, CHARLES H. HALL and JOHN ELDRIDGE, citizens of the United States, residing at Astoria, in the county of Clatsop and State of Oregon, have invented new and useful Improvements in Gold Separators and Amalgamators, of which the following is a specification.

Our invention relates to an apparatus which is designed to separate gold and other metals from associated sand, and generally to separate heavier from lighter substances by centrifugal action, and to simultaneously amalgamate such metals as are capable of amalgamation.

It comprises combinations and arrangements of parts and details of construction which will be more fully explained by reference to the accompanying drawings, in which—

Figure 1 is an elevation and partial section. Fig. 2 is an elevation at right angles with Fig. 1. Figs. 3 and 4 are sections showing modifications of the interior of the apparatus.

1 represents a frame-work upon which a vertical shaft 2 is journaled in bearings 3—4, and driven at high speed by a belt on pulley 5. Upon shaft 2 and revolving with it, is mounted a spider 6 to which is bolted a cylinder 7 having in its inside surface a number of grooves 8 extending entirely around the cylinder, and these may, if desired, be divided at frequent intervals by vertical partitions 9, the edges of which are set slightly back of those of grooves 8.

Grooves 8 are not necessarily, of the form shown; but may be made of any suitable shape, and there may also be a greater or less number than shown.

To the upper end of cylinder 7 is bolted a hood 10 having a cylindrical neck 11. Within hood 10 and also secured to shaft 2 is a conical disk 12 having a number of radial ribs 13, the outside edges of which extend beyond disk 12 and are turned off true and fitted closely to inside of hood 10 which is bored out to fit them. There may be a greater or less number of ribs 13 than shown, and they may be either straight or curved as best to suit the material being worked. Extending at an angle into the top of neck 11 is a suitable trough or spout 14 for feeding material into the machine; or this may be a pipe leading from a centrifugal or other pump.

Around the lower end of cylinder 7, and

extending for some distance below it, is a sheet iron casing 15, the front half of which is hung by slotted holes 16 upon bolts 17 so as to be easily removable. Below casing 15 is a discharge spout 18 having its outer end resting on stop 20.

In operation mercury or an amalgam is fed into the machine at the top, and striking the ribbed disk 12, is thrown outward by centrifugal action, and coming in contact with the curved inner surface of hood 10, is gradually forced downward, by gravity and the addition of more material above until it completely fills grooves 8. Sand containing metal to be separated is then fed into the top of machine through spout 14, along with a stream of water, and is at once caught by ribbed disk 12 and spread by centrifugal action around the inner surface of hood 10, and gradually forced downward over the mercury filled grooves 8. The mercury, owing to its specific gravity, retains its position in grooves 8; only the heavier metals displacing or amalgamating with it, and the lighter waste materials being forced downward and discharged through spout 18.

The cylinder 7 may be made slightly tapering—as in Fig. 3—in order to facilitate the flow of material through it; or the grooves 8 may be dispensed with altogether, as in Fig. 3, and the cylinder lined with amalgamated plates 21 of various shape according to the nature of material being worked.

Having thus described our invention, what we claim and desire to secure by Letters Patent is—

1. In an apparatus for separating and amalgamating metals, a hollow, vertically journaled, substantially cylindrical and revoluble barrel or chamber with annular horizontal grooves in its inner surface to retain mercury by centrifugal force, vertical partitions fitting said grooves, an upwardly convergent hood fixed to the top of the barrel, with an open top, said hood having interior horizontal, annular grooves, a cone fixed to and revoluble with the cylinder shaft, said cone having a less angle than the hood, radial vanes fixed to the cone with their outer edges in close proximity to the interior of the hood, a source of supply at the top of the hood, and a receiver and discharge beneath the apparatus.

2. In an apparatus of the character described, a substantially cylindrical barrel with an upwardly convergent superposed

hood, with means to supply material thereto, said hood and barrel having annular channels of different depths, a cone within the hood having radial vanes whose edges are in close proximity with the interior of the grooved hood, vertical intercepting diaphragms fitting the grooves of the barrel, a removable casing inclosing the lower part of the barrel, and a receiving floor and discharge chute.

In testimony whereof we have hereunto set 10
our hands in presence of two subscribing wit-
nesses.

CHARLES H. HALL.
JOHN ELDRIDGE.
